RECEPTACLE FOR SAFETY RAZOR BLADES

Kenneth B. Peterson, Brooklyn, N. Y.

Application March 2, 1951, Serial No. 213,552

1 Claim. (Cl. 30—40)

1

This invention relates to an attachment for safety razors, and more particularly for use in connection with those of the so-called "ejector" type wherein a used blade is ejected by the insertion of a new blade from a device which is detachably connected to the razor and which contains a supply of blades for successive insertion in the razor as needed.

When a used blade is ejected in the manner above described, it is pushed out of the razor with some degree of force and unless the razor is held at the time of blade-ejection over a table or other suitable surface, the blade will fall to the floor or to some inconvenient location making it difficult or uncomfortable to retrieve.

It is, therefore, an object of the present invention to provide a collection receptacle or holder for used and ejected blades so that as each blade is ejected from the razor on the insertion of a new blade, the ejected blade will be deposited directly into the collection receptacle or holder that is detachably secured to the razor, and the blade will thus be safely caught and stored for future disposal.

The invention contemplates the provision of a blade-collection or catch receptacle of this character which can be conveniently attached to and detached from the razor as required; which will act as a storage chamber for a number of the discharged and ejected blades and which, when full of the ejected blades, can be conveniently emptied.

More particularly, the invention contemplates the provision of a blade-receiving chamber or casing having means by which it may be coupled to the outlet end of the razor, and provided with an entrance opening through which an ejected blade will pass to thereby enter the blade-receiving chamber and be stored therein. Successive blades can thus be received in the blade-receiving chamber until the same is full, and the device then emptied.

These and other objects are attained by the invention, a more particular description of which will appear hereinafter and be set forth in the claims appended hereto.

In the accompanying drawing, wherein an illustrative embodiment of the invention is disclosed, Fig. 1 is a perspective view of the head portion of a razor of the ejector type, to which the improved blade-catching device is attached;

Fig. 2 is a side elevation of the blade-collection device;

Fig. 3 is a longitudinal sectional view through the blade-collection device, with the cap at one end of the device shown in elevation;

2

Fig. 4 is a top plan view of the same, with parts broken away and in section to clearly show the construction; and

Fig. 5 is a view looking at the forward or front end of the device.

Referring to the drawing, and particularly to Fig. 1 thereof, a razor of the so-called "ejector" type is shown at 1, the same having a seat on which the blade 2 is supported. In inserting a new blade in this type of razor, a blade-inserting device, a portion of which is shown at 3, is coupled to the entrance end of the razor, and by operation of a slide 4, a new blade is slid out of the inserting device 3 and caused to be moved into position on the seat of the razor. As the new blade is moved forward to position in the razor, it forces the used blade out of the razor or, in other words, ejects it. In the normal use of a razor of this character, the ejected blade is shifted out of the razor with some force and unless the razor is held at the time, over a table or other surface, the ejected blade may fall to the floor and be difficult to retrieve and unless retrieved become a hazard.

25 The improved collection receptacle is generally indicated at 5 and the same includes a casing 6 of rectangular and elongated form and of a shape to accommodate a number of collected blades. At the forward end of the casing is provided a coupling means for attaching it to the outlet end of the razor, such means including a pair of prong members or tongues 7 and 8, which are detachably accommodated in a slot at the outlet end of the razor in a manner similar to the way in which the blade-inserting device 3 is attached at the inlet end of the razor. The forward end of the casing 6 is partly closed by a wall or partition 9 which provides an inlet opening or slot 10 above it and through which the blades enter for reception within the casing 6.

30 35 40 45 50 55 Located within the casing 6 and extending longitudinally thereof, is a leaf spring 12 constituting a retainer for the blades delivered into the casing. At its forward end, the spring is bent backwardly upon itself, as indicated at 13 and this end portion of the spring is located within a slot 15 in the top wall 19 of the casing extending inwardly from its forward edge. An end portion 20 of the spring overlies the top of the casing and is attached thereto by means of the rivet 14 or equivalent fastening element. The spring 12 thus extends through the casing in such a manner as to exert resilient pressure upon the used blades as they reach the interior of the casing, such used blades being shown therein at 16. A slot or window opening 17 is

provided in at least one of the side walls of the casing so that the number of blades collected in the holder can be ascertained at a glance, and the holder emptied when full. The rear end of the casing 6 is closed by a removable cover or closure cap 11 which can be manually removed at any time to enable the collected blades to be emptied and suitably disposed of.

From the foregoing, the operation of the device will be readily understood: When a blade is ejected from the razor in the known manner herein described, and the collection device is attached to the outlet end of the razor with the slot-opening 10 in alignment with the end of the blade being ejected, the ejected blade will be slid directly from the razor and will pass through the inlet slot 10 of the holder to be received into the casing 6 and held under the spring 12. The collection device is then detached from the razor and the razor used in the conventional manner. The collection device can be used repeatedly for the collection of each ejected blade, until the holder becomes filled with the collected blades, and which can be ascertained by a glance through the aperture 17, whereupon the cap 11 may be removed and the blades dumped out for suitable disposal.

While I have herein illustrated a certain type of ejector razor to which the collection receptacle is attached, it will be understood that this has been done solely for the purpose of illustration, since the collection device is readily applicable to any type of razor in which a blade is ejected by an endwise sliding movement. Also, while I have herein illustrated the collection device as being attached to the outlet end of the razor by the two prongs or fingers 7 and 8, it will

be understood that other means of coupling the collection receptacle to the outlet end of the razor might readily be employed.

Thus, while I have herein shown and described a single embodiment of the invention, it is obvious that the same is not to be restricted thereto, but is broad enough to cover all structures coming within the scope of the annexed claim.

What I claim is:

A collection receptacle for safety razor blades comprising, a casing of a shape to accommodate a number of razor blades, said casing having an open rear end normally closed by a removable closure cap, a cap closing said rear end, the casing having a slot-opening at its forward end, and means for detachably coupling the casing to the outlet end of a razor in a position to locate the slot-opening in alignment with a blade seated on the razor, whereby an ejection of said blade from the razor will direct the same through the slot-opening and into the casing, spring means under which each blade is inserted as it enters the casing, the casing being attached to the razor in a manner to permit the blades to be inserted in the casing while the head of the razor is disposed uppermost.

KENNETH B. PETERSON.
